DISPLAY

Claude Carey Cloud, Chicago, Ill.

Application June 19, 1936, Serial No. 86,135

7 Claims. (Cl. 40—126)

This invention relates to displays for use in show windows or on counters or the like, and the primary object is to provide a display which may be collapsed into substantially a flat condition to facilitate shipping or other handling thereof and which when unfolded will provide a display of predetermined configuration.

Other important objects are to provide a three dimensional foreground in the display; to form the foreground from a blank consisting of a single piece of material and to form the background from a blank also consisting of a single piece of material; to score or otherwise provide fold lines in the blanks along which the blanks may be folded into predetermined configurations; to interconnect substantially all of the various parts of both the foreground and background of the display along fold lines and thereby reduce the number of adhesively secured portions to a minimum; and to print or otherwise arrange representations on one side only of the blanks.

Further objects are to provide a self-supporting display; to lock the display against collapsing after it has been folded into its predetermined configuration; to provide a substantially horizontal shelf or ledge in the foreground of the display intermediate integral but offset vertically extending parts of the foreground; to enable the interconnected foreground and background of the display to be shipped in substantially flat condition; to so interconnect the parts that they will automatically unfold into a predetermined configuration upon relative movement of parts of the background; and to provide a display of economical construction and simple and positive operation.

A selected embodiment of my invention is illustrated in the accompanying drawing wherein

Fig. 1 is a front elevational view of the display as arranged for use;

Fig. 2 is a front elevational view of the display in partially unfolded condition;

Fig. 3 is a plan of the blank for the foreground of the display;

Fig. 4 is a side elevation of the foreground of the display partially unfolded;

Fig. 5 is a plan of the blank for the background of the display; and

Fig. 6 is a rear elevation of the background of the display unfolded to arrange the display as shown in Fig. 1.

Displays of the kind to which my invention, as illustrated in the accompanying drawing, pertains are usually made of stiff paper, cardboard

or other analogous material although they may be made from foil or sheet metal or other material. In the present instance the blank BR of the foreground of the display is cut from stiff paper although it is to be understood that other material could be used if desired.

That part of the foreground of the display which is to constitute the back part of the foreground is provided at the upper part of the blank BR and is indicated by 7 in the drawing. The free marginal outline of this part 7 conforms to the nature of the display, that is to say, in the present instance where a bowl of fruit is drawn, painted, printed or otherwise provided on one face of the part 7 of the blank BR the free marginal outline of this part conforms to the outline of the fruit and bowl appearing adjacent this marginal edge.

In the completed display the part 7, as best shown in Fig. 1, extends vertically and a part 8 extends forwardly from the part 7 in a substantially horizontal plane, and in the present instance the top of a table is drawn, painted, printed or otherwise provided on the face of the part 8, that is to say, this is provided on the same face of the blank as that on which other representations are provided. A part 9 which extends vertically in the completed display at the forward end of the horizontal shelf 8 is offset in the completed display from the back part 7 and provides the forepart of the foreground of the display and a continuation of the drawing, painting or printed matter provided on the part 8 is, in the present instance, provided on the part 9.

The part 9 includes two substantially rectangular sections 9a and 9b which are preferably of equal size and which are interconnected along adjacent edges by a fold or score line 10 that extends at right angles to the lower edges of these sections. The outer edges of the sections 9a and 9b are longer than the edges of these sections joined along the fold line whereby the upper edges of these sections are inclined and the inclination of these upper edges is such that they extend at a slight obtuse angle to the fold line 10, the angles between these edges and the fold line being of equal size.

Aligned score lines 12 and 12' extend medially across the parts 7 and 8. The fold line 12 divides the part 7 into sections 7a and 7b while the fold line 12' divides the part 8 into sections 8a and 8b. The lower or inner end of the fold line 12' merges with the upper or inner end of the fold line 10 and the aligned fold lines 12 and 12' extend at an obtuse angle relative to the score line 10. The

angularity of the aligned fold lines 12 and 12' relative to the score line 10 is much greater than the angularity of the upper edges of the sections 9a and 9b.

- 5 The lower edge of the section 8a is connected to the upper edge of the section 9a along a fold or score line 11, which line constitutes the upper edge of the section 9a and the lower edge of the section 8a. The upper edge of the section 8a 10 is provided by a score line 13 along which the sections 8a and 7a are interconnected. The upper edge of the section 8b is connected to the section 7b along a fold or score line 14, which score line constitutes the upper edge of the section 8b and the lower edge of the section 7b. 15 The score lines 13 and 14 merge at the juncture of the score lines 12 and 12' and these score lines 13 and 14 extend at an obtuse angle relative to the score lines 12 and 12'. 20 The score lines 11 and 13 merge in alignment with the upper end of the outer edge of the section 9a whereby the section 8a is of substantially triangular outline, the base being afforded by the fold line 12'. 25 The lower edge 8c of the section 8b extends from the juncture of the fold or score lines 10 and 12'. By referring to Fig. 1 it will be seen that the score lines 11 and 12' define an acute angle therebetween and the angularity of the 30 extent of the edge 8c is such that an acute angle is defined between the edge 8c and the score line 12' and this acute angle is congruent to that defined between the score lines 11 and 12'. A part of the edge 8c is defined by a score line 16 35 which interconnects a tab 15 to the section 8b. The score lines 16 and 14 merge whereby the section 8b is of substantially rectangular outline and has the score line 12' as the base thereof. The sections 8a and 8b of the part 8 are 40 congruent.

The specific inclination of the inclined score lines in the blank BR and the inclination of the edge 8c and of the top edge of the section 9b is such that when the various parts are properly 45 interconnected and the foreground of the display is folded along the score lines it will assume a predetermined configuration.

In initially interconnecting the parts to assemble the display, the sections 7a and 8a are folded 50 along the score line 11 to extend rearwardly from the face of the section 9a shown in Fig. 3. Then the section 7a is folded relative to the section 8a so as to extend vertically in offset relation with respect to the section 9a. Simultaneously with 55 this the section 8c is folded to extend forwardly relative to the section 7b. Then the section 9b is folded rearwardly along the score line 10 until it comes into engagement with the tab 15. A suitable adhesive is applied to the face of the tab 15 or to the rear side of the section 9b along the 60 upper edge thereof so that when the tab 15 and section 9b come into engagement these parts may be firmly interconnected. The tab 15 is so secured to the section 9b that the fold line 16 is aligned with the upper edge of the section 9b. The section 8a will then extend at right angles to both the sections 9a and 7a and the section 8b 65 will extend at right angles to the sections 9a and 7b. When the parts are so arranged the foreground of the display will be in its predetermined configuration.

After the tab 15 has been adhesively secured in position continued movement of the section 9b toward the section 9a will result in folding of 70 the section 7b toward the section 7a and the

face of the section 8a shown in Fig. 3 will move toward the face of the section 7a shown in that view and similar relative movement between the faces of the sections 8a and 7b will occur whereby the foreground of the display may be folded into 75 substantially flat condition.

As best shown in Fig. 3, a tab 17 is provided outwardly of the section 9a and a tab 18 is provided outwardly of the section 9b. Tab 17 is joined to the section 9a along a fold or score line 19 and the tab 18 is connected to the section 9b along a fold or score line 20. The tabs 18 and 17 are used to secure the foreground of the display to the background thereof.

In the present instance a blank BR is cut from 15 cardboard or other stiff material and provides the background of the display. The background is generally indicated by 21 and includes two sections 21a and 21b which are substantially rectangular in outline and which have adjacent 20 edges thereof joined along a fold or score line 22.

A tongue 23 is cut from the sections 21a and 21b so as to extend in substantially equal amounts on opposite sides of the fold line 22 and this tongue is entirely free from the section 21b but 25 is joined to the section 21a along a fold or score line 24 which extends at an acute angle relative to the fold line 22.

The tongue 23 is adapted to be folded downwardly from the blank as viewed in Fig. 5 and 30 then when the faces of the sections 21a and 21b of the background 21 opposite those appearing in Fig. 5 are folded toward each other, as shown in Fig. 6, the edge 25 in the section 21b along which the tongue 23 was cut therefrom enters 35 the notch 26 cut in that part of the tongue 23 adjacent this edge 25 in the blank as shown in Fig. 5, and the entrance of the edge 25 into the notch 26, as shown in Fig. 6, limits relative movement between the sections 21a and 21b and this 40 lock holds the sections 21a and 21b in the positions of these sections shown in Figs. 1 and 6.

Suitable adhesive is provided on the faces of the tabs 17 and 18 opposite those shown in Fig. 3 or at the lower outer corners of the sections 45 21a and 21b on the faces thereof shown in Fig. 1 whereby the tabs 17 and 18 may be secured to the faces of the sections 21a and 21b appearing in Fig. 1 at the lower outer corners thereof.

The lower edges of the tabs 17 and 18 and 50 sections 9a and 9b are aligned with the lower edges of the sections 21a and 21b and when the display is arranged for use it is rested on these edges.

The interconnection of the tabs 17 and 18 to 55 the background 21 is such that when the edge 25 is engaged in the notch 26 the display will be arranged as shown in Fig. 1, in which position the sections 8a and 8b extend horizontally and the display will have attained its predetermined 60 configuration and be ready for use. This position is attained by moving the faces of the sections 21a and 21b appearing in Figs. 1 and 2 away from each other, an intermediate position in this movement being shown in Fig. 2.

In initially assembling the display, the foreground is first formed in the manner described and then the sections 21a and 21b of the background are positioned as shown in Fig. 1 whereupon the tabs 17 and 18 are secured to the background. In order to facilitate shipping and handling of this completed display the faces of the sections 21a and 21b appearing in Fig. 1 are folded toward each other into the position shown in Fig. 2 whereby the foreground collapses 75

between sections 21a and 21b and a flat package is provided. The display is shipped in this condition and when it reaches the user it is only necessary that the faces of the sections 21a and 21b appearing in Fig. 1 be moved away from each other until the position shown in Fig. 1 is attained whereupon the edge 25 is engaged in the notch 26 and the display is assembled ready for use.

It will be apparent from the foregoing description that I have provided a display embodying a three dimensional foreground and that the foreground is made from a single piece of material and that only one adhesive interconnection need be provided between the various parts. By reason of the inclination of the score lines as 12 and 12' relative to a score line in the forepart of the display elimination of adhesively secured parts is attained and the foreground may therefore be formed from a single piece of material. The particular inclination of score lines as 12 and 12' is determined from other dimensions in the display but the inclination will always be such that when the display is arranged in its final form the inclined score lines will be aligned with the score line relative to which they are inclined. Furthermore, representations need be provided on but one face of the blanks.

While I have illustrated and described a preferred form of my invention it is to be understood that this is capable of variation and modification and I therefore do not wish to be limited to the precise details set forth but desire to avail myself of such changes and alterations as fall within the scope of the following claims:

I claim:

1. A display of predetermined configuration including a forepart, a back part, and an intermediate part, each of said parts being divided into sections by fold lines extended thereacross, one section of the intermediate part being connected to a section of the forepart and to a section of the back part along fold lines, another section of the intermediate part being connected to another section of the back part along a fold line and having a tab connected thereto along the fold line, said tab being adhesively connected to another section of the forepart, said forepart and said back part being folded along the fold lines therein in the completed display to dispose the sections thereof in substantially vertical planes and also to dispose the sections of each of said parts in angular relation with each other, said intermediate part being disposed in a substantially horizontal plane when the sections of the forepart and the back part are disposed in vertical planes.

2. A display of predetermined configuration including a forepart, a back part, and an intermediate part, each of said parts being divided into sections by fold lines extended thereacross, one section of the intermediate part being connected to a section of the forepart and to a section of the back part along fold lines, another section of the intermediate part being connected to another section of the back part along a fold line and having a tab connected thereto along the fold line, said tab being adhesively connected to another section of the forepart, said forepart and said back part being folded along the fold lines therein in the completed display to dispose the sections thereof in substantially vertical planes and also to dispose the sections of each of said parts in angular relation with each other, said intermediate part being disposed in a sub-

stantially horizontal plane when the sections of the forepart and the back part are disposed in vertical planes, said display being collapsible into a substantially flat package when adjacent faces of the angularly disposed sections of the forepart and the back part are moved toward each other, corresponding faces on the sections of the intermediate part moving from said substantially horizontal plane toward said adjacent faces of the sections of the forepart and the opposite faces of said intermediate sections moving toward the faces of the sections of the back part opposite said adjacent faces thereof when said adjacent faces of the forepart and back part are moved toward each other, relative movement of said adjacent faces of said sections of the forepart and the back part away from each other when said display is collapsed into a flat package causing said intermediate part to return to said horizontal plane, the return of said intermediate part to said horizontal plane limiting movement of said sections of the forepart and back part and arranging said display in said predetermined configuration.

3. A display formed from the blank comprising interconnecting portions providing a forepart, a back part and an intermediate part in the display, each of said portions having a fold line extended thereacross substantially medially thereof dividing said parts into sections, adjacent edges of the back and intermediate part providing portions being interconnected along fold lines, adjacent edges of one section of the forepart providing portion and one section of the intermediate part providing portion being interconnected along fold lines, adjacent edges of the other section of the forepart providing portion and the other section of the intermediate part providing portion extending in angular relation one with the other, and a tab disposed along a part of one of the angularly extending edges and interconnected to the section of which said edge is a part along a fold line, the fold lines extending across said back and intermediate part providing portions being aligned one with the other and extending at an obtuse angle relative to the fold line extended across the forepart providing portion whereby when said portions are folded along said fold lines to dispose the back part providing portion and the forepart providing portion in vertical planes the intermediate part providing portion will be disposed in a horizontal plane and said tab will be disposed adjacent the section of which the other of said angularly extending edges is a part and the fold lines extending across said back and intermediate part providing portions will be aligned with the fold line extending across said forepart providing portion.

4. A display formed from the blank comprising interconnecting portions providing a forepart, a back part and an intermediate part in the display, each of said portions having a fold line extended thereacross substantially medially thereof dividing said parts into sections, adjacent edges of the back and intermediate part providing portions being interconnected along fold lines, adjacent edges of one section of the forepart providing portion and one section of the intermediate part providing portion being interconnected along fold lines, adjacent edges of the other section of the forepart providing portion and the other section of the intermediate part providing portion extending in angular relation one with the other, and a tab disposed along a part of one of the angularly extending edges and

interconnected to the section of which said edge is a part along a fold line, the fold lines extending across said back and intermediate part providing portions being aligned one with the other 5 and extending at an obtuse angle relative to the fold line extended across the forepart providing portion whereby when said portions are folded along said fold lines to dispose the back part providing portion and the forepart providing portion in vertical planes the intermediate part providing portion will be disposed in a horizontal plane and said tab will be disposed adjacent the section of which the other of said angularly extending edges is a part and the fold lines extending across said back and intermediate part providing portions will be aligned with the fold line extending across said forepart providing portion, the fold lines along which the back and intermediate part providing portions are interconnected 10 merging with the opposite edges of the sections of the intermediate part providing portion in spaced relation with the fold line extending medially across the intermediate part providing portion whereby the sections of the intermediate part providing portions are of substantially triangular outline.

5. A display including a foreground and a background each formed from a single piece of material, the background being adapted to be disposed in a vertical plane, the foreground including a forepart and a back part each disposed in vertical planes and in offset relation and also an intermediate part interconnecting the forepart and back part and disposed in a substantially horizontal plane when the forepart and the back part are disposed in vertical planes, the forepart of said foreground being connected to the background, said foreground and background having fold lines extending substantially medially thereacross in aligned relation whereby the foreground and background may be folded on these fold lines into a substantially flat package, the foreground including fold lines intermediate the parts thereof along which the parts of the foreground may fold when the foreground and background are folded into a substantially flat package, the fold lines intermediate the parts of the foreground being disposed to cause said foreground to unfold into predetermined configuration.

30

35

40

45

figuration upon movement of sections of the background on opposite sides of the fold line therein relative to each other.

6. A display including a foreground and a background each formed from a single piece of material, the background being adapted to be disposed in a vertical plane, the foreground including a forepart and a back part each disposed in vertical planes and in offset relation and also an intermediate part interconnecting the forepart and back part and disposed in a substantially horizontal plane when the forepart and the back part are disposed in vertical planes, the forepart of said foreground being connected to the background, said foreground and background having fold lines extending substantially medially thereacross in aligned relation whereby the foreground and background may be folded on these fold lines into a substantially flat package, the foreground including fold lines intermediate the parts thereof along which the parts of the foreground may fold when the foreground and background are folded into a substantially flat package, the fold lines intermediate the parts of the foreground being disposed to cause said foreground to unfold into predetermined configuration upon movement of sections of the background on opposite sides of the fold line therein relative to each other, and means integral with the background and having a notch therein into which a part of the background may be fitted to hold said background and foreground against movement when the foreground is arranged in predetermined configuration.

7. A background for a display or the like having a fold line extending thereacross dividing it into sections, a tab struck from said background or the like to extend on opposite sides of the fold line extended thereacross, said tab having an edge thereof connected to one section of said background or the like and having a notch in the portion thereof on the opposite side from said background connection into which an edge on the other section of the background may be fitted to thereby hold said sections of the background in predetermined angular relation one with the other.

CLAUDE CAREY CLOUD.
